UNITED STATES PATENT OFFICE

150,195

DESIGN FOR A KICKING TEE

Mell M. Barton, San Marino, Calif., assignor to
W. J. Voit Rubber Corporation, Los Angeles,
Calif., a corporation of California

Application June 7, 1947, Serial No. 139,519

Term of patent 14 years

(Cl. D34—5)

To all whom it may concern:

Be it known that I, Mell M. Barton, a citizen of the United States, residing at San Marino, in the county of Los Angeles and State of California, have invented a new, original, and ornamental Design for Kicking Tee, of which the following is a specification, reference being had to the accompanying drawing, forming part thereof, in which:

Fig. 1 is a perspective view of a kicking tee, showing my new design; and

Fig. 2 is an elevational view thereof.

I claim:

The ornamental design for a kicking tee, as shown.

MELL M. BARTON.
